MEANS FOR FLOWING WELLS

Hans C. Glitsch, Dallas, Tex., assignor to Fritz W. Glitsch & Sons, Dallas, Tex., a partnership consisting of Fritz W. Glitsch, Sr., Fritz W. Glitsch, Jr., and Hans C. Glitsch

Application March 11, 1940, Serial No. 323,417

13 Claims. (Cl. 103—232)

This invention relates to new and useful improvements in means for flowing wells.

In the production of petroleum products from wells, it has become the general practice to utilize an auxiliary lifting fluid, such as gas or air, for raising the well fluids to the surface, such auxiliary lifting fluid being introduced into the well below the liquid level therein. For controlling the introduction of the lifting fluid into the liquid column, various types of flow apparatuses have been employed, the most common of which are referred to as "flow valves." The usual type of flow valve is arranged to be automatically operated by the pressure differential thereacross and ordinarily, one side of the valve is exposed to the pressure of the lifting gas with the opposite side exposed to the pressure of the well liquid, whereby the differential in such pressures actuates the valve.

In many instances, a spring or other means, is arranged so that its force is added to one of the pressures so that the differential at which the valve operates may be predetermined and controlled. However, when the usual valve has once been set for a predetermined differential, it is opened, as well as closed, at such differential and cannot be operated at other differentials without changing the size of the various operating parts or strength of the springs. Even such change, although it does vary the particular operating differential, does not permit an independent adjustment of the differential at which the valve closes, as compared to the differential at which the valve opens and this is a serious disadvantage.

In many instances, a spring or other means, is arranged so that its expansive force is utilized to create the differential at which the valve operates. In such valves, the flexible range between the opening and closing differentials is very limited, so it may be stated, that for practical application, the opening and closing differentials are at the same point. Various devices have been, and may be, employed to change the operating differentials of the usual valve. It is characteristic of ordinary valves that the factors which control the closing differential likewise directly affect the opening differential of the valve. It follows that the one can not be changed without changing the other. Similarly, it is true that the volumetric rate at which such valves will admit the lifting fluid is a direct function of the differential thereof. It may then be stated that in the conventional valve, a change in differential will effect a change in the rate of admission

of lifting fluid and that a change for the purpose of restricting the rate of passage of lifting fluid will affect the characteristics of the valve, and may affect the differential either directly or indirectly.

Further, some of the flow valves, now in general use, employ pistons or other sliding elements for effecting a seal or closure, and as is well known, it is very difficult to obtain a fluid tight seal by means of a sliding element; also, in the usual valve, the control of the volume of lifting fluid which is introduced usually affects the differential at which the valve operates since no provision is made for an independent control of volume. If the control of the volume of lifting fluid is attempted in the usual valve by changing of port sizes or passages by or through the valve ports the closing differential is usually affected adversely because of back pressuring at the outlet side of the valve or decrease in effective piston area subjected to the closing pressure. The above disadvantages are objectionable and the presence of any one of such disadvantages in a valve impairs the efficient operation of the valve.

It is one of the objects of the present invention to provide an improved means for controlling the admission of an auxiliary lifting fluid, such as gas or air, into a well liquid column, said means being constructed so as to overcome the disadvantages present in the usual control means of this kind.

An important object of the invention is to provide an improved flow apparatus having a valve element which is actuated by the pressure differential thereacross and which is so arranged that the differential required to close the valve element may be controlled independently of the differential required to open said element, whereby the apparatus may be set to assure a predetermined well liquid column to be built up in the well before the lifting gas is admitted and at the same time provide for a closing of the valve element as soon as sufficient lifting fluid has been admitted to efficiently lift the particular column of liquid, thereby conserving the lifting fluid and preventing undue waste thereof.

Another object of the invention is to provide an improved means for controlling the admittance of a lifting gas into a well liquid column which includes a control element actuated by the differential between the pressure of the lifting gas and the pressure of the well liquid to introduce gas into a liquid column when a predetermined differential is reached, whereby the gas is admitted into the liquid and raises the same, together with

means for closing off the admittance of gas when a predetermined pressure differential across the element occurs, the latter differential being different, and even less, than the differential at which the gas was admitted, whereby an accurate control of the lifting gas may be maintained under any well conditions.

A particular object of the invention is to provide an improved flow apparatus having a movable valve element which is adapted to be moved from opened to closed position by the pressure differential thereacross, said element being constructed so that its direction of movement may be changed at any point in its travel, whereby said valve may be fully reopened at any point in its closing cycle or closed at any point in its opening cycle, thereby providing for quick and efficient operation in accordance with pressure conditions.

Still another object of the invention is to provide an improved flow apparatus for controlling the admission of a lifting gas into a well liquid column having means for positively adjusting and controlling the volume of gas introduced upon each actuation of the device, said means being entirely separate from the actuating parts of the device, whereby an adjustment or change in the volume of gas admitted does not subject the valve element to a back pressuring prior to the admittance of the gas to the fluid column and, therefore, does not affect or change the differential, or differentials, at which the device operates.

A further object of the invention is to provide an improved flow apparatus, of the character described, wherein a piston type valve element is employed for controlling the flow of lifting gas into the liquid column, said element having a valve seat associated therewith, whereby when the element moves to a closed position, the seat provides a positive shut-off to prevent leakage past the element.

Another object of the invention is to provide an improved flow apparatus, of the character described, having a valve element which is adapted to open the inlet to a full-open position upon initial opening movement, whereby substantially no restriction to the flow of admitted gas is had as it enters the liquid column; said valve element also being adapted to substantially cut off all flow upon its initial closing movement, thereby making for a "snap-action," and thus providing a quick-opening and quick-closing valve.

A particular object of the invention is to provide an improved flow apparatus including a valve element which is rotatable, as well as movable longitudinally, whereby the advantages of both a rotary and sliding type of valve element are combined in the single member.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a transverse, vertical sectional view of a flow apparatus, constructed in accordance with the invention, the valve element being shown in its closed position.

Figure 2 is an enlarged transverse, sectional view of a portion of the apparatus with the valve element in its lowered or closed position.

Figure 3 is a view, taken on the line 3—3 of Figure 2, with the valve element in its raised or open position.

Figure 4 is a horizontal, cross-sectional view, taken on the line 4—4 of Figure 1.

Figure 5 is a horizontal, cross-sectional view, taken on the line 5—5 of Figure 1.

Figure 6 is a horizontal, cross-sectional view, taken on the line 6—6 of Figure 1.

Figure 7 is a horizontal, cross-sectional view, taken on the line 7—7 of Figure 1.

Figure 28 is a horizontal, cross-sectional view, taken on the line 28—28 of Figure 26, and

Figures 29 to 31 are views, similar to Figure 28, illustrating the operation of the spring which imparts rotation to the valve element during longitudinal movement thereof.

In the drawings, the numeral 10 designates a well casing which extends axially through a well bore. The lower end of the casing is open and communicates with the producing formation, whereby the well liquid may flow into the casing and then upwardly therethrough to the surface. A well tubing 11 extends axially through the well casing substantially throughout its length and serves to conduct an auxiliary lifting fluid, such as gas and air, downwardly to the lower portion of the casing below the well liquid level, as will be explained. For controlling the flow of the lifting gas or air from the well tubing 11 and into the liquid standing within the well casing, the improved flow apparatus A is pro-

75

vided and this apparatus is arranged to be coupled to the lower end of the tubing 11, as is clearly shown in Figure 1. The apparatus is actuated by predetermined pressure differentials thereacross and is constructed so as to admit the lifting gas into the well liquid after said liquid has risen to a predetermined height within the well casing 10. As soon as the liquid column is moved upwardly by the admitted auxiliary lifting gas, then the apparatus is arranged to shut off the flow of gas. The device remains in a closed or shut-off position until such time as sufficient well liquid has again entered the casing 10 from the producing formation and has risen to a predetermined height therein, after which the operation is repeated. Although the apparatus A is shown as controlling the flow of the auxiliary gas from the tubing into the well casing, it is pointed out that said device could control the admittance of gas from the upper portion of the casing into the well tubing, such arrangement being employed if the well tubing 11 is utilized as the liquid conductor, with the well casing employed as the auxiliary gas conductor. In this instance, it would, of course, be sometimes necessary to employ a packer, as is the usual practice.

The improved flow apparatus A includes an elongate tubular body portion 12 which has its upper end coupled to the tubing 11 by means of a suitable coupling collar 12'. The lower end of the tubular body 12 has a cylinder 13 connected thereto, and this cylinder is provided with an axial bore 14 which extends entirely therethrough. The lower end of the cylinder has a coupling collar 15 secured thereto and an elongate tubular plug member 16 is threaded onto the lower end of the collar 15. The lower portion of the plug 16 has a plurality of radial ports 17 provided therein, whereby the interior of the plug will communicate with the bore of the well casing 10 so that pressure from said casing may enter the interior of the plug.

A cylindrical valve element or piston 20 has a sliding fit within the bore 14 of the cylinder 13 and, as is clearly shown in Figures 3, 10, and 11, a pair of diametrically opposed flutes or grooves 21 are formed in the exterior wall of the piston. The piston 20 is movable longitudinally in the bore 14 and is also rotatable therein, as will be hereinafter explained. A rotation of the piston within the bore 14 of the cylinder permits an alinement of the flutes 21 with a pair of diametrically opposed ports 22, which ports are formed in and extend through the wall of the cylinder 13 (Figure 11). The upper end of the piston is formed with an external annular shoulder or flange 23 and the lower end of this flange is beveled to form a seating surface 24. The inclined seating surface 24 is arranged to engage a seat 25 provided at the upper end of the bore 14 of the cylinder 13. When the surface 24 engages the valve seat 25, it will be manifest that a closing off of the bore 14 will be effected and, also, further downward movement of the piston 20 within said bore is prevented. When the piston is moved upwardly so as to move the seating surface 24 off the seat 25, as shown in Figure 3, a flow of gas may occur from above the cylinder, downwardly through the flutes 21 in the piston and then through the ports 22 provided in the cylinder wall. Therefore, when the piston is in its lowest position, a flow through the ports 22 is impossible. An upward movement of the piston 20, together with an alinement of

the flutes 21 with the ports 22 permits a flow from above the piston outwardly through said ports 22.

For controlling the volume of gas which passes from the ports 22 and then into the interior of the casing 10, a collar 26 is provided and this collar surrounds the cylinder 13. As is clearly shown in Figure 3, the collar 26 has its lower end threaded to the upper end of the coupling 15, while its upper end abuts an external shoulder 27 which is formed on the cylinder 13. The collar 26 has a plurality of outlet ports 28 extending through its side wall and the area of these ports controls the amount or the volume of gas which flows into the interior of the well casing 10. Manifestly, the collar 26 is readily removable and may be replaced by another collar having smaller or larger ports 28, whereby the volume of gas entering the casing may be readily varied. It is noted that the collar is entirely separate from the movable valve element or piston 20 and, therefore, any change in the size of the ports in the collar 26 will not affect the operation of the piston 20.

As explained, the downward movement of the piston 20 is limited by the external flange 23 formed at the upper end of the piston. For limiting the upward movement of the piston 20, said piston has an externally threaded pin 29 formed on its lower end. This pin receives an adjusting nut 30, which has a diameter larger than the diameter of the piston 20, said nut being movable within the bore of the tubular plug 16, as is clearly shown in Figure 1. The nut 30 may be moved to various positions on the pin 29 and upon upward movement of the piston, will strike the underside of the coupling 15 to limit the upward movement of said piston. Obviously, the position of the nut on the pin 29 will control the movement which the piston may undergo in its upward travel.

The piston is formed with an integral cylindrical extension 32 which extends upwardly through the tubular body 12 and also through the coupling 12' and into the lower end of the tubing 11. This extension is provided with a reduced portion 31 which is immediately above the external flange 23. The provision of the reduced portion 31 forms an external shoulder 33 on the extension. For guiding the extension in its axial movement as the piston 20 undergoes movement, a guide collar 34 is mounted within the coupling 12' and said collar is formed with vertical passages 35, whereby the lifting gas from the tubing may pass downwardly through said collar and into the tubular body 12 of the apparatus. The extreme upper end of the extension 33 is reduced and externally screw-threaded to provide an elongate threaded screw 36. A coil spring 37 surrounds the reduced upper end of the extension and has its lower end resting on the guide collar 34 which is fixed within the bore of the coupling 13. The upper end of the spring engages a bearing collar 38 which forms the lower race of a bearing assembly 39. The upper race of the assembly is in the form of a nut 40 which is threaded onto the elongate pin 36. Obviously, the collar 34 is rotatable with relation to the nut 40. Since the coil spring 37 is confined between the stationary guide collar 34 and the bearing collar 38 which is mounted on the extension 32, it is obvious that said spring exerts its pressure to constantly urge the extension, and also the piston which is a part of said extension, upwardly, whereby the piston is constantly urged toward its raised or open position. By adjusting the nut 40 vertically

on the elongate screw 36, the tension on the spring 37 may be varied, whereby said spring exerts a predetermined pressure in urging the valve element toward its upper position. For locking the nut 40 in various adjusted positions, on the elongate pin 36, said pin is provided with a vertical slot 41 (Figure 4), while the nut has a radial opening 42 formed therein. The nut also has an annular channel 43 within which a spring 44 is arranged to engage. The spring has an inwardly extending pin 45 formed thereon and this pin is arranged to extend through the radial opening 42 of the nut with its inner end engaging the vertical slot or channel 41 of the elongate pin 36 when and so engaged, the nut 40 is locked on the screw-threaded pin 36 and is incapable of rotation thereon. The purpose of the bearing assembly 39 is to permit the adjusting nut 40 to rotate with the piston 20 and its extension 32, while permitting the coil spring 37 and its collar 38 to remain stationary, whereby friction during rotation of the valve element is reduced.

As has been explained, the well liquids enter the lower end of the well casing 10 and rise upwardly therein. The pressure of the liquid column within the well casing may act against the lower end of the piston 20 because of the communication between the interior of the plug 16 and the interior of the casing through the ports 17. This pressure, which will be herein-after referred to as the casing pressure, is added to the force exerted by the coil spring 37 in urging the piston 20 and its associate parts, to a raised or opened position. The upward movement or opening of the valve element is resisted by the pressure of the auxiliary lifting gas which is introduced into the upper end of the well tubing 11 and which is acting downwardly on the upper end of the valve element. Thus, the pressure of the lifting gas serves to urge the valve element toward a closed position, while the pressure within the well casing, plus the pressure of the coil spring 37 is acting to move said element in an opposite direction toward an open position.

Ordinarily, the pressure of the lifting gas is in excess of any pressure which is built up by the liquid column within the well casing and for the purposes of this description, it will be assumed that the lifting gas pressure is 400 pounds. This pressure of 400 pounds is acting downwardly on the valve element to hold the piston 20 in its lowered position, as shown in Figures 1 and 2. The force or pressure exerted by the coil spring 37 is, of course, subject to variation by an adjustment of the nut 40 and this pressure acts oppositely to the pressure of the lifting gas. For example, the spring pressure or force may be 300 pounds. In addition to the coil spring 37, the pressure within the casing 10 also acts upwardly against the bottom of the piston 20. If the lifting gas pressure is 400 pounds and the spring pressure is 300 pounds, it becomes apparent that when the pressure in the casing builds up in excess of 100 pounds, the piston 20 will be moved upwardly toward an open position. Under these conditions, the opening differential which is established is the difference between the pressure of the lifting gas, which is 400 pounds, and the pressure in the casing which is 100 pounds, or a difference of 300 pounds.

Upon the initial upward movement of the piston 20 a rotating mechanism B, which will be hereinafter described, serves to impart a rotation to the piston. Such a rotation alines the longitudinal flutes 21 in the piston with the radial

ports 22 in the cylinder 13, whereby said ports 22 are opened to receive a flow of the lifting gas. The initial upward movement of the piston 20 lifts the flange 23 off its seat 25 and thus the gas 5 may flow downwardly from the tubing 11 through the passages 35 in the guide sleeve 34, through the tubular body portion 12 and then downwardly through the longitudinal flutes 21 and the openings 22 in the cylinder 13. The gas then flows 10 through the outlet ports 23 in the control collar 26, which ports control the volume or amount of gas introduced. As the gas enters the liquid column within the well casing 10, the pressure in the casing is built up, whereby this pressure 15 is added to the normal casing pressure and acts against the underside of the piston 20 to force the piston upwardly to the position shown in Figure 3. The piston will, of course, continue upward movement until the nut 30 which is secured 20 to the threaded pin 29 on the lower end of the piston strikes the lower end of the cylinder, at which time further upward movement of the valve element is prevented. During the interval that the valve element is completing its 25 upward travel, the lifting gas is constantly admitted to the liquid column in the casing 10 and this gas will begin to move the column upwardly.

It has been found that prior to the time that the liquid column begins its upward movement, the pressure in the well casing 10 is built up by 30 the introduced or admitted lifting gas until such pressure approaches the pressure of said lifting gas. However, this pressure never reaches the same pressure as the lifting gas although it may 35 approach the same relatively closely. Of course, as soon as the column begins to move upwardly and the velocity of said column is gradually increased, the pressure in the casing 10 begins to fall. Upon being lowered to a predetermined 40 point, the valve element begins to move downwardly and upon such initial downward movement, the rotary mechanism B imparts rotation to the piston 20, whereby the flutes 21 are again misaligned with the outlet ports 22 in the cylinder 45 wall so that immediately, substantially all of the gas supplied to the casing is shut off.

The pressure differential at which the valve element begins its downward movement is different from the pressure differential which was 50 required to open said valve element. It will be remembered that a 300 pound opening differential was established due to the fact that the coil spring 37 was exerting substantially a 300 pound pressure at the time that the valve is in its fully 55 closed position. However, as the valve moved upwardly to an open position, the spring 37 expanded, whereby its force, as exerted against the valve element, is reduced. The exact reduction in the force exerted by the spring is obviously 60 controlled by the amount of movement of the valve element which movement is, in turn, controlled by the adjustment of the nut 30 on the lower end of the piston 20. Thus, it is possible 65 to permit the valve element to move upwardly any desired distance so that the spring is extended to the point where its force, as exerted against the piston, is reduced to a predetermined point, as for example, 100 pounds. Thus, when 70 the valve element has completed its upward movement, the coil spring 37 is exerting only 100 pounds pressure in an upward direction on said valve element. The pressure of the lifting gas within the tubing remains substantially constant and is still exerting approximately 400 pounds 75 downwardly on said valve element. However,

since the gas has been admitted into the casing and the pressure in said casing has been built up to substantially 350 pounds, it will be manifest that this casing pressure, plus the pressure of the expanded spring 37, is sufficient to hold the valve in an open position. As the pressure in the casing begins to drop due to the lifting of the liquid column, the force exerted against the underside of the piston 20 is reduced. When this pressure falls to slightly less than 300 pounds, the valve element 20 will begin to move downwardly. The initial downward movement will result in a rotation of the valve element, whereby the flutes 21 in the piston are moved out of alignment with the ports 22 to shut off substantially all flow of gas into the casing. Thus, it will be seen that the closing differential is the difference between the 400 pounds lifting gas pressure and the 300 pounds pressure in the well casing 10, which difference is 100 pounds. The valve thus closes at a differential of only 100 pounds, whereas a differential of 300 pounds will open said valve.

From the above, it will be obvious that the coil spring 37 controls the opening differential, that is, by adjusting the nut 40, said spring may be arranged to cause the valve to open when the pressure within the casing reaches any predetermined proportion of the pressure of the lifting gas in the tubing 11. The closing differential which is necessary to actuate the valve element 20 is controlled by the adjusting nut 30 which is threaded on the pin 29 at the lower end of the piston 20. By adjusting this nut, it is possible to accurately control the exact amount of travel which the valve element undergoes in moving upwardly. This travel will in turn control the amount of expansion of the spring 37 and will, therefore, definitely control the reduction in the force exerted by such spring. The force which the spring 37 is exerting when the valve element is in its fully raised position is the controlling factor in determining what pressure is present in the casing 10 at the time that the valve starts toward its closed position. Therefore, the adjusting nut 30 controls the closing differential. This nut is entirely separate from the adjusting nut 40 which varies the pressure of the spring 37 when the valve element is fully closed and, therefore, the closing differential may be independently and separately adjusted relative to the opening differential.

With this arrangement, it is possible to provide a high opening differential, whereby a predetermined liquid column must be built up in the well casing 10 before the valve element moves upwardly to admit the lifting gas. Of course, after the valve has opened and admitted sufficient gas beneath the liquid head to lift said head to the surface, it is desirable to close the valve as soon thereafter as possible so as to conserve the lifting gas. The apparatus shown permits the valve to have a low closing differential available so that it will immediately close after the liquid column has been moved upwardly. As has been explained, when the piston 20 is in its lowered or shut-off position, the longitudinal flutes 21 in said piston are misaligned with the ports 22 provided in the cylinder wall 13 (Figure 10). Upon initial upward movement on the piston 20, a rotation is imparted to said piston so as to align the flutes 21 with said ports. Similarly, when the piston is in its uppermost position, as shown in Figure 3, the flutes 21 are aligned with the ports 22 and upon initial down-

ward movement of said piston, a reverse rotation is imparted to the piston, whereby the flutes are returned to their misaligned position with respect to the ports 22. Various types of mechanisms and devices which may be employed for imparting this partial rotation to the piston 20 so as to produce the desired co-action between the flutes 21 and the ports 22 and thereby effect an opening and closing of the flow of gas. However, it is preferable to employ the mechanism B, which is clearly illustrated in Figures 1 to 19, and particularly in Figures 15 to 19.

The mechanism B includes an elongate sleeve 50 which is mounted within the bore of the tubular body 12 and is non-rotatably confined between the upper end of the cylinder 13 and the lower end of the guide collar 34 (Figure 3). This sleeve is provided with an elongate vertical slot or opening 51 which is substantially semi-circular in cross-section, as is clearly shown in Figures 6 and 7. A semicircular shoe 52 is slidably mounted within the elongate slot 51 and this shoe is formed with an inclined slot 53 which extends entirely therethrough. A radially extending pin 54 engages within the slot 53 of the shoe and this pin is fastened within the extension 32 of the valve element. When the valve element is in its lowermost or shut-off position, as shown in Figure 2, the pin 54 is in the lower end of the slot 53 (Figure 12). As the valve element begins to move upwardly, the shoe 52 is locked against upward movement, as will be explained, whereby the pin 54 is caused to move upwardly through the slot 53 in said shoe. As said pin moves upwardly in the slot 53, a rotation is imparted to the extension 32 as well as to the piston 20 and such rotation is sufficient to align the flutes 21 with the openings 22 in the cylinder wall. When the pin reaches the upper end of the slot 53, the shoe 52 is released so that a continued upward movement of the valve element will result in a simultaneous upward movement of the shoe 52 within the slot 51 of the sleeve 50.

When the valve element is in its raised position, the pin 54 is in the upper end of the slot 53 of said shoe, as shown in Figures 3 and 13, said pin having been moved to such position upon the upward movement of the valve element. Upon the initial downward movement of the valve element due to the proper pressure differential, the shoe 52 is again locked against movement and the pin 54 is caused to travel downwardly through the slot 53. Such a downward movement of the pin through the slot 53 results in a reverse rotation of the extension 32 and the piston 20, whereby the flutes 21 in said piston are again misaligned with the ports 22 in the cylinder 13. As soon as this occurs, the flow of gas through said flutes and into the interior of the casing is shut off. As soon as the pin 54 reaches the bottom of the slot 53, the shoe 52 is released, whereby a continued downward movement of the valve element will result in a downward movement of the shoe 52 within the slot 51 of its sleeve 50. Thus, it will be seen that the valve element is a combination rotary and slide valve. Upon initial upward movement, the flutes 21 are first aligned with the ports 22, whereby a substantially unrestricted flow of gas is permitted past the valve element. The ports remain in this position until upward travel of the valve element is complete, at which time a downward movement of said element causes a rotation to immediately shut off the flow of gas thereby.

For locking the arcuate shoe 52 against movement upon the initial movement in a given direction of the valve element, a locking member 55 is provided (Figure 14). This member includes an arcuate body portion 56 which is arranged to fit snugly about the reduced portion 31 of the extension 32. The body 56 is formed with a vertical rib 57 which extends through a slot 58 provided in the sleeve 50. The rib 57 has a transverse width which is less than the width of the slot 58, whereby a space 59 is provided between one vertical wall of the rib and the side of the slot. A suitable spring member 60 (Figure 19) has one end secured in the wall of the rib 57 and is adapted to bear against the end or side wall of the slot 58, whereby the rib is frictionally held against movement within the slot 58. Of course, a sufficient force exerted against the member 55 will result in a vertical sliding movement of the member, the rib 57 moving through the slot while the arcuate body of said member slides on the reduced portion 31 of the extension 32.

The body portion 56 on the member 55 is formed with a radially extending locking block 61, which block is adapted to abut one end wall of the slot 51 which is formed in the sleeve 50 (Figure 7). One vertical wall of the block 61 is formed with a pair of inclined locking faces 62 and 62a, as is clearly shown in Figures 14 to 18. The block extends into a slot 63 which is formed in one end of the arcuate shoe 52 and the vertical wall of said slot is provided with inclined faces 63a and 63b and these faces are adapted to co-act with the inclined faces 62 and 62a of the block 61.

In the operation of the locking mechanism, reference is made to Figure 15, wherein the parts are shown in a position with the valve element 20 in its lowered or closed position. In such position, the locking block 61 is located at substantially the central portion of the slot 63 and the pin 54 is disposed at the lower end of the inclined slot 53 of the arcuate shoe 52. It is noted that the locking member 55 is frictionally held in this position by means of the spring member 60 which is holding the rib 57 on said locking member in frictional engagement with one side wall of said slot. Upon initial upward movement of the valve element 20, the pin 54 which is secured to said element bears against the inclined slot 53 of the arcuate shoe 52 and moves said shoe upwardly therewith. The shoe is permitted to move to the position shown in Figure 16, whereby the inclined face 63b of the slot in said shoe strikes the inclined face 62a of the block 61. The block has, of course, been held stationary during such movement due to the spring 60 holding the same frictionally in a fixed position. As soon as the inclined face 63b of the slot 63 moves into engagement with the inclined face 62a of the block 61, the cam action which occurs by virtue of the inclined faces, causes the arcuate shoe 52 to move outwardly into engagement with the wall of the tubular body 12, whereby a frictional engagement sufficient to prevent further movement of the shoe is accomplished.

As soon as the arcuate shoe 52 is locked against further movement, a continued upward movement of the valve element causes the pin 54 to travel upwardly in the inclined slot 53 and such travel imparts a rotary motion to the valve element 20. As explained, such rotation of the valve element results in an alinement of the

longitudinal flutes 21 with the ports 22. Of course, the initial upward movement of the valve element unseated the flange 23 from its seat 25 and as soon as the flutes are lined with the ports 22, a flow of gas may occur into the casing.

Just prior to the time that the pin 54 which is carried by the element 20 moves into the upper end of the slot 53 of the shoe 52, the external shoulder 23 formed at the upper end of the piston 20 strikes the underside of the locking member 55, as is clearly shown in Figure 17. As soon as the flange engages the underside of the member 55, said member is moved upwardly with the valve element 20. Of course, at this time, the shoe 52 is incapable of movement. As the block 61 is moved upwardly with relation to the shoe 52, said block moves to the position shown in Figure 18, at which position, the cam action between the co-acting faces of the block and the slot 63 permit an inward movement of the shoe, whereby the frictional engagement of the shoe, with the wall of the body 12, is released. After this occurs, a continued upward movement of the piston 20 results in a similar upward movement of both the shoe 52 and the locking member 55.

When the element has completed its upward travel, as determined by the adjustment of the limiting nut 30, the parts are in the position shown in Figure 3, in which position the pin 54 is at the upper end of the inclined slot 53 within the shoe. Upon the initial downward movement of the valve element, the pin 54 bears downwardly on one side of the slot 53, whereby a downward movement is imparted to the shoe. At this time, the locking block 61 is held stationary by the friction set up by the spring 60, as has been explained. As the shoe moves downwardly with relation to the locking block, the co-acting faces 62 and 63a result in an outward or radial movement of the shoe 52, whereby said shoe is frictionally locked against movement. A continued movement of the valve element in a downward direction causes the pin 54 to traverse the slot 53 in said shoe, whereby said element is rotated to again misalign the flutes 21 with the ports 22 in the cylinder. As soon as this occurs, substantially all flow of gas from the tubing is shut off. Just prior to the time that the pin 54 reaches the extreme lower end of the inclined slot 53, the external shoulder 33 on the extension 32 strikes the upper end of the locking element or member 55. This results in a downward movement of the locking member with relation to the shoe 52, whereby the locking block is again moved to the central portion of the shoe 52. Such movement of the block 61 to the central portion of the slot 63 permits a slight inward movement of the shoe 52, whereby its frictional grip on the wall of the body 12 is released. After this is accomplished, a continued downward movement of the valve element will result in a simultaneous downward movement of both the shoe 52 and the locking member 55.

From the above, it will be seen that the mechanism B provides a simple and effective means whereby the valve element may be rotated upon initial movement in either direction. Upon upward movement, the valve is rotated to align the flutes with the ports 22 in the cylinder and thereby admit gas to the casing. Upon initial downward movement of the valve element, the element is rotated back to its original position misaligning the flutes with the openings 22, whereby the gas is shut off. The arrangement makes for a

full opening and full closing immediately upon movement of the valve member. At the initial opening, the ports are substantially wide open and there is no restriction of the flow. It is further pointed out, that the mechanism shown permits the valve element to move any desired amount or any desired distance. A change in direction at any point in the cycle results in an operation of the locking member 55 and shoe 52. Thus, it is possible to change direction of travel of the valve element at any point between wide open and completely closed position. This is an important feature of the invention for it permits the closing differential, as controlled by the adjusting nut 30, to be varied over a wide range.

In the operation of the device, the flow apparatus is connected to the lower end of the tubing 11 and is lowered therewith into the well casing. At such time, the lifting gas is introduced into the tubing and moves the valve element 20 to its lower position, as shown in Figures 1 and 2. The lifting gas pressure is acting downwardly on the valve element, while the pressure within the casing 10 is acting upwardly against said element, such casing pressure entering the tubular plug 16 through the port 17, as has been explained. The casing pressure is assisted in urging the valve element upwardly toward an open position against the lifting gas pressure by the coil spring 37. This spring may be adjusted by the nut 40, whereby a predetermined pressure must be built up in the casing before the valve element 20 is moved upwardly.

When the predetermined pressure is built up within the casing through the building up of a liquid column therein, the valve 20 begins to move upwardly. As it does so, the arcuate shoe 52 is raised sufficiently with relation to the locking block 61 to lock said sleeve against movement within the tubular body 12. As soon as this occurs, a continued upward movement of the valve element 20 causes the pin 54 carried by said element to move upwardly in the inclined slot 53 in the arcuate shoe 52. Such movement imparts a rotation to the valve element, whereby the longitudinal flutes 21 in said element are alined with the ports 22 in the cylinder wall. The lifting of the valve element lifts the annular flange 23 off its seat 25 and as soon as the flutes 21 are lined with the ports, gas may flow from the tubing downwardly past the seat 25, through the flutes 21, and out through the ports 22. The gas then flows through the outlet 28 in the control collar 26 and into the casing to act against the liquid column therein.

As soon as the flutes 21 have been alined with the ports 22, the locking block 61 is moved upwardly within the slot 63 of the arcuate shoe 52 so as to permit said shoe to release its frictional grip on the wall of the body 12, after which the arcuate shoe and locking block 61 move upwardly with the valve member 20. Upward movement of said element continues until the adjusting nut 30 strikes the underside of the cylinder within which the valve piston is movable.

The valve remains in an open position until the pressure in the casing drops to a point where the pressure of the lifting gas acting on the upper end of the valve element is sufficient to overcome such pressure, plus the pressure of the spring 37. As soon as this occurs, the valve element begins to move downwardly and upon initial downward movement the arcuate shoe 52 is again locked against the wall of the tubular body 12, whereby

the pin 54 on the valve element is again caused to travel downwardly through the inclined slot 53 of said shoe. Such travel causes the valve element to be rotated so as to misaline the flutes 21 with the outlet ports 22 and thereby shut off the flow of gas to the casing. A continued downward movement of the valve element will result in a release of the frictional engagement between the shoe and the body 12, whereby said shoe, as well as the locking block may move downwardly with the valve element. Upon reaching its lowermost position, the annular flange 23 having the seating surface 24 engages the seat 25 to provide a fluid-tight seal at this point. Therefore, the shutting off effected by misalinement of the flutes 21 and the ports 22 is not alone depended upon to seal off the gas from the casing. The seating surface 24 and the seat 25 provide a positive shut-off, whereby no matter how long said valve may remain closed, any leakage of the gas into the casing is obviated.

The opening differential or the differential in pressures required to start the valve element upwardly toward its open position is controlled by the adjustment of the nut 40 which controls the pressure exerted by the spring 37. The closing differential is controlled by adjusting nut 30, which limits the upward movement of the valve element and also controls the reduction in the force of the spring 37 due to the expansion of said spring, as has been explained. These adjustments are entirely separate and distinct and, therefore, the closing differential may be adjusted independently of the opening differential, and vice versa. The volume or amount of gas which is introduced upon actuation of the valve element 20 is controlled by the size of the openings 28 in the collar 26 which surrounds the cylinder 13. This collar is readily removable and may be removed at any time, whereby another collar having different sized openings 28 may be substituted therefor. In this manner, the volume of gas which is introduced into the well casing may be controlled independently of the adjustment made with respect to the necessary differentials for operation of the valve element 20. Manifestly, the valve element 20 need not traverse its entire path of travel as it may move any desired distance and then start in a reverse direction. Whether the valve moves entirely from the position shown in Figure 2 to that shown in Figure 3 or whether it moves only a part of such distance, the locking mechanism, as well as the arcuate shoe 52 will operate in exactly the same manner. Whenever the direction of travel of the element is reversed, these parts come into action to first rotate the valve element and then permit the remainder of the longitudinal travel to be completed.

As has been stated, various types of rotary mechanisms may be provided for imparting the necessary rotation to the valve element 20 upon initial movement thereof and in Figures 20 to 23, a modified form of mechanism has been shown. In this form, a sleeve 50a is substituted for the sleeve 50 in the form shown in Figures 1 to 19. This sleeve is of a smaller diameter than the sleeve 50 and is confined between the guide collar 34 and the upper end of the cylinder 13. The sleeve is formed with lateral ports 70 which establish a communication between the well tubing 11 and the bore 14 on the cylinder. An elongate slot 71 is formed in the wall of the sleeve 50a and a bracket 72 spans the central portion of the

slot. A pivoted latch member 73 having its ends reduced, as shown in Figures 20 and 23, is pivotally mounted on a suitable pin 14 and said latch is arranged to swing transversely within the slot. A spring 75 has one end engaging an outwardly extending pin 76 formed on one end of the latch 73, while its opposite end is fixed to the outer surface of the sleeve 50a below the slot. The spring 75 serves to hold the latch 73 in the position shown in Figure 20.

The valve element 20 is provided with an outwardly extending pin 77, which projects into the slot 71 of the sleeve. When the valve element is in its lowered position, closing off the gas supply to the casing, the pin is in the position shown in Figure 20. Upon initial upward movement of the valve element, the pin 77 strikes the edge of the latch member 73 and is guided upwardly along the curved surface thereof. Continued upward movement of the element causes the pin to travel upwardly between the latch member and one side of the slot 71 and such travel of the pin imparts a rotation to the valve element. It is this rotation which alines the flutes 21 in the valve element with the openings 22 in the cylinder as has been explained.

As the pin 77 moves upwardly toward the upper end of the latch member 73, the latch member is forced to swing under tension of the spring 75, whereby the pin is permitted to move into the upper end of the slot 71. As soon as the pin passes the upper end of the latch member 73, the spring 75 immediately moves the latch member back to its original position which is that shown in Figure 20. It is manifest that the arrangement causes a rotation to be imparted to the valve element, which rotation alines the flutes 21 with the ports 22 and permits an admission of gas into the well casing.

Upon downward movement of the valve element 20 toward its closed position, the pin 77 carried by said element rides the opposite edge of the latch member 73. The engagement of the pin with this edge of the latch member causes the pin to rotate the element back to its original position. As the pin approaches the lower end of the latch member, said member is again swung under tension of the spring 75, whereby the pin 77 may again move below said latch member. During the travel of the pin in this manner, the valve element is rotated to again misalign the flutes 21 with the ports 22, whereby the flow of gas into the casing is again shut off. The spring 37 is provided in this form and functions in the same manner to urge the valve element upwardly. In addition, an auxiliary light spring 37a is illustrated, this spring being disposed above the heavier spring 37. With this arrangement, the heavy spring may be utilized to load the valve for obtaining the opening differential, the lighter or weaker spring 37a being present to provide a wide range of flexibility in setting for the closing differential. In other words, the light spring controls the closing differential and the heavy spring aids the loading to obtain the large opening differential after the valve has rotated to a closure. Although the lighter spring 37a has not been illustrated on the form shown in Figures 1 to 19, it is obvious that, if desired, it may be used thereon.

Still another form of mechanism for imparting rotation to the valve element is disclosed in Figures 24 to 31. In this form, an elongate sleeve 50b is substituted for the sleeve 50a disclosed in Figure 20, and said sleeve is formed with an

elongate slot or opening 80 in one side thereof. A plate 81 covers the opening 80 and has a pair of guide members 82 secured to its inner face, such guide members projecting into the opening 80. As is clearly shown in Figure 24, the guide members 82 are arranged so as to form a vertical passage 83 at one side of the opening 80 and a second vertical passage 84 at the opposite side of said opening. These vertical passages are connected by an inclined passage 85 near their upper end and are also connected at their lower end due to the fact that the lower guide member 82 terminates short of the lower end of the slot 80. The opposite side of the sleeve 50b is formed with a narrow slot 86 which has a vertical portion 87 at its lower end and a vertical portion 88 at its upper end, said portion being connected by an inclined portion 89.

The piston 20 of the valve element is formed with a head 90 which is located above the seating surface 24 at the upper end of said piston. The head has the extension 32 threaded thereinto, as is clearly shown in Figure 27. The head is provided with an upwardly extending annular flange 91, which flange is provided with slots 92 and 93, as is clearly shown in Figures 28 to 31. A cap member 94 is rotatable on the lower end of the extension 32 and is provided with a depending flange 95 which surrounds the flange 91. The flange 95 is formed with slots or openings 92a and 93a, which slots, are complementary to the slots 92 and 93 of the flange 91. A coil spring 96 is wound around the extension 32 and is confined below the cap member 94 and within the flange 91. One end 96a of the spring is bent radially outwardly and abuts one end of the slots 92 and 92a of the flanges 91 and 95. The opposite end 96b of the spring 96 is bent outwardly so as to engage one end of the slots 93 and 93a of the flanges 91 and 95. Obviously, with this arrangement, a rotation of either one of the members 90 or 94 will result in placing the torsion spring 96 under tension, whereby the force of said spring will always tend to maintain the parts in alignment with each other, that is, with the slots 92 and 92a, as well as the slots 93 and 93a, in alined position.

The head 90 which is preferably made integral with the valve element 20 is provided with a radially extending pin 97, which pin extends outwardly into the slot 80 and is adapted to traverse the passages 83, 84 and 85 formed therein by the guide members 82. The cap member 94 is provided with a similar pin 98 which rides within the inclined slot 86 which is formed in the opposite side of the sleeve member 50b.

In the operation of this form, when the valve element is in its lowered position, as shown in Figure 24, the pin 97 is at one side of the slot 80 below the guide members 82. At this time, the flutes 21 in the valve member 20 are alined with the outlet ports 22 in the wall of the cylinder 13. It is noted that in the other forms hereinbefore described, when the valve element is lowered, the flutes are misaligned. However, in the present form, said flutes are in alined position so that the only seal is at the seating surface 24. At the time that the pin 97 is in the position shown in Figure 24, the pin 98 which is secured to the cap member 94 is in a position shown in Figure 25. At this time, the torsion spring 96 is as shown in Figure 28 with the flanges 91 and 95 having their respective slots alined with each other.

When the valve element 20 is moved upwardly

by the differential in pressures thereacross, the pin 97 moves upwardly into the passage 83 formed between one vertical edge of the slot 80 and the lowermost guide member 82. During such movement, the pin 98 moves from a position in the lower end of the slot 86 to the point marked 98a in Figure 25, and up to this time, the spring 96 remains in the same position as shown in Figure 28. A continued upward movement of the valve element causes the pin 97 to move upwardly in the passage 83 to the position indicated at 97a in Figure 24. During the time that the pin 97 is completing its movement to this position, the pin 98 and the cap member 94 is traversing the inclined portion 89 of the slot 86 and then travels upwardly through the vertical portion 88. As the pin 98 moves through the inclined portion 89 or the slot 86, a rotation is imparted to the cap member 94, whereby said cap member rotates with relation to the head 90. The head is, of course, held stationary by the confinement of this pin 97 within the passage 83.

The rotation of the cap member 94 with relation to the head 90 causes a winding of the torsion spring 96, as is clearly shown in Figure 29, whereby said spring is placed under pressure. The parts remain in this position until a downward movement of the valve element occurs. Upon such a downward movement, the pin 97 which is secured to the head 90, travels downwardly along the edge of the upper guide member 82, and due to the pressure of the spring which is tending to rotate the head 90, said pin moves downwardly into the inclined passage 85. Such downward movement of the pin imparts a rotation to the valve element 20, whereby the flutes 21 in said element are misaligned with the outlet ports 22 and a flow of gas is shut off. It is pointed out that at the time that the pin 97 moves to the position 97b within the passage 85, the pin 98 on the cap member is in the position indicated at 98b in Figure 25. In such position, it is still holding the end 96b of the spring 96 in the position shown in Figure 29. Manifestly, a continued downward movement of the valve element will cause the pin 97 to move downwardly through the passage 84 to the lower end of the slot 80. By the time the pin 97 has moved into the passage 84, a sufficient rotation has been imparted to the head 90 and valve element 20 to cause the flanges 91 and 95 to again align their respective slots 92, 92a, 93 and 93a, as is shown in Figure 30.

At the time that the pin 97 starts downwardly through the passage 84, the pin 98 on the cap member 94 again travels downwardly through the inclined portion 89 of the slot 86. Such travel of the pin through the inclined portion of this slot results in a rotation of the cap member 94 with relation to the head 90, whereby the spring 96 is again placed under tension as is shown in Figure 31. At this time, the head 90 cannot be rotated because the pin 97 is confined in the passage 84. However, as soon as said pin leaves the lower end of the passage 84, the tension of the spring immediately rotates the head 90 and the valve element 20 to the position shown in Figures 24 and 28. Such rotation again aligns the flutes 21 of the valve element with the outlet ports 22 but the gas is shut off from the casing by the seating surface 24 engaging its seat 25.

From the foregoing it will be obvious that the torsional spring 96 is utilized to impart the necessary rotation to the valve element 20. The ele-

ment is guided in its movement and also in its rotation by the passages 83, 84 and 85 which are provided by means of the guide members 82. It is again noted that in this form of the invention, the flutes 21 are aligned with the outlet ports 22 when the valve is in its lowered or closed position, the shutting off of the gas being effected by the seating surface 24 and the seat 25. When the valve reaches the upper end of its movement and begins a downward movement, it is rotated so as to misalign the flutes and shut off the admission of gas. Upon reaching the lower end of its travel, a rotation is imparted to again align the flutes, but only after the seat 24 has shut off the gas. It is noted that in this form of the invention the inclined passage 85 may be inclined in a direction opposite to that shown so that the valve will be caused to close on the build up of pressure under the column of fluid, while the valve element is moving upwardly. The pin 97 following the slot 85 would close the gas passage by rotating the valve element to misalign the ports.

In all forms of the invention, the advantages of a rotary and a sliding valve are combined. Also, in all forms, the differentials at which the valve element are opened and closed may be of different values predetermined and established. Although only a single valve has been shown and described, it is obvious that a plurality of valves may be connected in a well tubing or flow string, the valves being properly spaced in superposed relation in the usual manner. In such case, said valves would function as flow valves for flowing high volume wells and each valve may be adjusted so as to have the predetermined opening and closing differential, in accordance with the particular flow conditions.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A flow apparatus including, a tubular valve body having a passage therein with lateral ports extending from the passage, a valve element having a sliding fit within the passage and having its upper end exposed to the pressure thereabove and its lower end exposed to the pressure in the passage below the element so as to be actuated by the differential in pressures on opposite sides thereof, said element having vertical flow passages therein which are adapted to be aligned with the lateral ports to permit a flow past the element and outwardly through the ports and also being arranged to be misaligned with said ports to shut off the flow, and means for rotating the valve element upon its initial movement toward an open position so as to align the flow passages with the ports, said last named means also imparting rotation to the element upon initial movement toward a closed position, whereby a full opening and full closing is had immediately following the initial movement of the valve element.

2. A flow apparatus including, a tubular valve body having a passage therein with lateral ports extending from the passage, a valve element having a sliding fit within the passage and having its upper end exposed to the pressure thereabove and its lower end exposed to the pressure in the passage below the element so as to be

actuated by the differential in pressures on opposite sides thereof, said element having vertical flow passages therein which are adapted to be aligned with the lateral ports to permit a flow past the element and outwardly through the ports and also being arranged to be misaligned with said ports to shut off the flow, means for rotating the valve element upon its initial movement toward an open position so as to align the flow passages with the ports, said last named means also imparting rotation to the element upon initial movement toward a closed position, whereby a full opening and full closing is had immediately following the initial movement of the valve element, and means associated with the valve element for accurately controlling the pressure differential at which the valve element is opened and closed.

3. A flow apparatus including, a tubular valve body having a passage therein with lateral ports extending from the passage, a valve element having a sliding fit within the passage and having its upper end exposed to the pressure thereabove and its lower end exposed to the pressure in the passage below the element so as to be actuated by the differential in pressures on opposite sides thereof, said element having vertical flow passages therein which are adapted to be aligned with the lateral ports to permit a flow past the element and outwardly through the ports and also being arranged to be misaligned with said ports to shut off the flow, means for rotating the valve element upon its initial movement toward an open position so as to align the flow passages with the ports, said last named means also imparting rotation to the element upon initial movement toward a closed position, whereby a full opening and full closing is had immediately following the initial movement of the valve element, and a removable sleeve mounted on the body surrounding the lateral ports and having ports of predetermined size so as to control the volume of flow which is emitted through the apparatus.

4. A flow apparatus including, a tubular valve body having a passage therein with lateral ports extending from the passage, a valve element having a sliding fit within the passage and having its upper end exposed to the pressure thereabove and its lower end exposed to the pressure in the passage below the element so as to be actuated by the differential in pressures on opposite sides thereof, said element having vertical flow passages therein which are adapted to be aligned with the lateral ports to permit a flow past the element and outwardly through the ports and also being arranged to be misaligned with said ports to shut off the flow, means for rotating the valve element upon its initial movement toward an open position so as to align the flow passages with the ports, said last named means also imparting rotation to the element upon initial movement toward a closed position, whereby a full opening and full closing is had immediately following the initial movement of the valve element, an annular valve seat within the body, and a valve member secured to the valve element and adapted to engage the seat when the element is in a fully closed position to provide a positive fluid seal.

5. A well flow device including in combination with a well liquid conductor and a lifting gas conductor, a tubular body connected with the gas conductor and having a lateral outlet port for emitting the lifting gas into the liquid conductor, a valve element slidable within the bore of the

body and co-acting with the port for controlling the flow of gas through the port, said element having its upper end exposed to the pressure of the gas in the gas conductor with its lower end exposed to the pressure of the well liquid in the liquid conductor so as to be operable by the differential in such pressures, and means for independently controlling the differential required to open the valve element and the differential required to close said element.

6. A well flow device including in combination with a well liquid conductor and a lifting gas conductor, a tubular body connected with the gas conductor and having a lateral outlet port for emitting the lifting gas into the liquid conductor, a valve element slidable within the bore of the body and co-acting with the port for controlling the flow of gas through the port, said element having its upper end exposed to the pressure of the gas in the gas conductor with its lower end exposed to the pressure of the well liquid in the liquid conductor so as to be operable by the differential in such pressures, a coiled spring associated with the element and exerting its force to urge the valve to an open position, means for varying the tension on said spring so as to control the pressure differential required to open the element, and an adjustable stop for limiting the movement of the element during its opening movement, whereby the amount of expansion of the spring during such opening movement may be varied to control the pressure differential which is required to cause the valve element to be moved toward its closed position.

7. A well flow device including in combination with a well liquid conductor and a lifting gas conductor, a tubular body connected with the gas conductor and having a lateral outlet port for emitting the lifting gas into the liquid conductor, a combination rotary and slide valve element within the bore of the body and co-acting with the port for controlling the flow of gas through the port, said element having its upper end exposed to the pressure of the gas in the gas conductor with its lower end exposed to the pressure of the well liquid in the liquid conductor so as to be operable by the differential in such pressures, and means for independently controlling the differential required to open the valve element and the differential required to close said element.

8. A flow apparatus for wells including, a pair of conductors extending through the well, one of said conductors being adapted to conduct the well liquids to the surface and the other being arranged to conduct a lifting gas downwardly below the liquid level, a valve assembly connected in the gas conductor and having a valve element for controlling the flow of gas from said conductor into the well liquid in the liquid conductor, means for exposing one side of the valve element to the pressure of the lifting gas in the gas conductor, means for exposing the opposite side of the valve element to the well liquid pressure in the liquid conductor, whereby the valve element is opened and closed to admit and shut off gas to the liquid column by the differential in such pressure, means associated with the valve element for accurately controlling the differential at which the element is opened and the differential at which the valve is closed, and means for controlling the volume of gas admitted to the liquid column upon opening of the valve, said means being so arranged that the valve is not subjected to back pressuring upon such change in

volume, whereby the differentials at which the valve is actuated are unaffected by such change.

9. A well flow device including in combination with a well liquid conductor and a lifting gas conductor, a tubular body connected with the gas conductor and having a lateral outlet port for emitting the lifting gas into the liquid conductor, a valve element slidable within the bore of the body and co-acting with the port for controlling the flow of gas through the port, means for exposing the upper end of the valve element to the pressure of the gas in the gas conductor means for exposing the lower end of said element to the pressure of the well liquid in the liquid conductor whereby the valve element is operable by the differential in such pressures, a heavy loading spring associated with the element and exerting its force to urge the valve to an open position and being capable of adjustment to obtain the desired opening differential, a relatively light spring also associated with the element and adjustable independently of the heavy spring, said light spring providing for increased flexibility in varying the closing differential for the valve element, and an adjustable stop for limiting the movement of the element during its opening movement, whereby the amount of expansion of the springs during such opening movement may be varied to control the pressure differential which is required to cause the valve element to be moved toward its closed position.

10. A well flow device including in combination with a well liquid conductor and a lifting gas conductor, a tubular body connected with the gas conductor and having a lateral outlet port for emitting the lifting gas into the liquid conductor, a combination rotary and slide valve element within the bore of the body and co-acting with the port for controlling the flow of gas through the port, means for exposing the upper end of the valve element to the pressure of the gas in the gas conductor, means for exposing the lower end of said element to the pressure of the well liquid in the liquid conductor whereby said element is operable by the differential in such pressures, a movable sleeve within the body surrounding the valve element and having an inclined slot therein, a pin on the valve element engageable within the slot, and clutching means actuated by longitudinal movement of the valve element for locking the sleeve against movement upon the initial travel of the valve in either direction, whereby the pin co-acts with the slot upon such initial travel of the valve element to impart a rotation to the element and thereby affect opening or closing of the outlet port to control flow through said port.

11. A well flow device including in combination with a well liquid conductor and a lifting gas conductor, a tubular body connected with the gas conductor and having a lateral outlet port for emitting the lifting gas into the liquid conductor, a combination rotary and slide valve element within the bore of the body and co-acting with the port for controlling the flow of gas through the port, means for exposing the upper end of the valve element to the pressure of the gas in the gas conductor, means for exposing the lower end of said element to the pressure of the well liquid in the liquid conductor whereby the valve element is operable by the differential in such pressures, a movable sleeve within the body surrounding the valve element and having an in-

clined slot therein, a pin on the valve element engageable within the slot, and clutching means actuated by longitudinal movement of the valve element for locking the sleeve against movement upon the initial travel of the valve in either direction, whereby the pin co-acts with the slot upon such initial travel of the valve element to impart a rotation to the element and thereby affect opening or closing of the outlet part to control flow through said part, said clutching means being constructed so as to automatically release the sleeve when the pin has traversed the slot and rotation of the valve element is complete, whereby further longitudinal movement of the valve element through the body is possible.

12. A well flow device including in combination with a well liquid conductor and a lifting gas conductor, a tubular body connected with the gas conductor and having a lateral outlet port for emitting the lifting gas into the liquid conductor, a combination rotary and slide valve element within the bore of the body and co-acting with the port for controlling the flow of gas through the port, means for exposing the upper end of the valve element to the pressure of the gas in the gas conductor, means for exposing the lower end of said element to the pressure of the well liquid in the liquid conductor whereby said valve element is operable by the differential in such pressures, a stationary sleeve within the body surrounding the valve element and having a vertical opening therein, a latch mounted in the opening and pivoted at substantially mid-height thereof, whereby the spaces between the vertical edges of the opening and the longitudinal edges of the latch form passages, a flexible means holding the latch in an inclined position with the lower end of said latch in engagement with one vertical edge of the opening, and a pin on the valve element movable within the passages formed between the latch and edges of the opening and adapted to co-act with these parts to affect a rotation of the valve element upon longitudinal movement thereof.

13. A well flow device including in combination with a well liquid conductor and a lifting gas conductor, a tubular body connected with the gas conductor and having a lateral outlet port for emitting the lifting gas into the liquid conductor, a combination rotary and slide valve element within the bore of the body and co-acting with the port for controlling the flow of gas through the port, means for exposing the upper end of the valve element to the pressure of the gas in the gas conductor, means for exposing the lower end of said valve element to the pressure of the well liquid in the liquid conductor whereby the valve element is operable by the differential in such pressures, a stationary sleeve surrounding the valve element and having vertical passages therein, said vertical passages being connected by an inclined lateral passage at their upper ends and by a horizontal passage at their lower ends, a pin carried by the valve element and movable through the passages to impart a rotation to said element upon longitudinal movement thereof, and a torsion spring associated with the valve element for causing the pin to move through the lateral passages when it is aligned therewith, whereby rotation of the valve element is assured.
